UNITED STATES PATENT OFFICE.

HENRY L. ZIMMERMAN, OF LONE TREE, IOWA.

STUMP-PULLING APPARATUS.

1,202,143.

Specification of Letters Patent. Patented Oct. 24, 1916.

Application filed October 24, 1914. Serial No. 868,473.

To all whom it may concern:

Be it known that I, HENRY L. ZIMMERMAN, a citizen of the United States, residing at Lone Tree, in the county of Johnson and 5 State of Iowa, have invented certain new and useful Improvements in Stump-Pulling Apparatus, and I do hereby declare the following to be a full, clear, and exact description of the invention, such as will enable 10 others skilled in the art to which it appertains to make and use the same.

This invention relates to improvements in stump pulling apparatus, and more particularly to the mechanism for controlling 15 and actuating the cable carrying drum.

An object in view is the provision of extremely simple and yet efficient means for engaging and disengaging the drum actuating mechanism with the drum, and a further object is the provision of means for relieving 20 the drum when released from operative engagement with the actuating mechanism of frictional engagement therewith.

A further object in view is the provision 25 of means for obviating danger of breakage or other injury to parts of the mechanism incident to misplacing of parts thereof.

With these and further objects in view, as will in part hereinafter be stated and in 30 part become apparent, the invention comprises certain novel constructions, combinations and arrangements of parts as will be hereinafter specified and claimed.

In the accompanying drawing, Figure 1 35 is a view, partly in side elevation and partly in vertical, central section, of an apparatus embodying the features of the present invention. Figs. 2 and 3 are detail, fragmentary, vertical, central sectional views, the 40 parts seen in Fig. 2 being in their disconnected position, and in Fig. 3 in their connected position. Fig. 4 is a fragmentary section taken on the plane indicated by line 4-4 of Fig. 2, parts being seen in plan. Fig. 45 5 is a vertical section taken on the plane indicated by line 5-5 of Fig. 2. Figs. 6 and 7 are fragmentary, detail views showing the pawl in elevation. Fig. 8 is an end view of the pawl detached. Fig. 9 is a detail view 50 partly in elevation and partly in section of one of the disk eccentrics detached. Fig. 10 is a detail section taken on the plane indicated by line 10-10 of Fig. 1. Fig. 11 is a 55 plan view of a modified form of key or clutch sleeve. Fig. 12 is a fragmentary section on line 12-12 of Fig. 5. Fig. 13 is a fragmen-

tary section taken on the plane of line 13-13 of Fig. 3.

Referring to the drawing by numerals, 1 indicates the frame of a stump puller having the usual hook 2 adapted to receive an anchoring cable. The upper portion of the frame is formed with an aperture 3 coaxial with an aperture 4 formed in the lower portion of the frame. A cylinder 5 snugly fits 60 within aperture 3 and is formed with a depending tubular shaft 6 which extends through and finds bearing in aperture 4. A drum 7 surrounds shaft 6 and is formed at at its upper portion with a squared aperture 70 snugly receiving the rectangular portion 8 at the upper end of shaft 6, the shaft 6 being introduced longitudinally through aperture 3 with its finger 9 threaded through a notch 9' formed in the upper portion of frame 1 and opening into aperture 3, the finger being disposed in an appropriate recess in the upper end of drum 7 and thus underhanging the frame 1 so as to prevent vertical escape of the parts. 75

The cylinder 5 is formed with internal teeth producing an internal ratchet 10 adapted to be engaged by a key sleeve or ratchet sleeve 11 shaped to snugly fit the ratchet 10. Extending axially through 80 sleeve 11 is a shaft 12 which extends down into shaft 6 to a point near the lower end thereof. The upper end of shaft 12 carries, and is preferably formed integral with, a box 13 adapted to receive a sweep or other 85 operating mechanism. External ratchet teeth 14 extend along and outstand from the upper portion of a shaft 12. The teeth of ratchet 14 extend longitudinally from the underface of box 13 down to the upper 90 end of shaft 6 and conform in contour to the inner ratchet of sleeve 11. Sleeve 11 is slidingly mounted on ratchet 14 so that said sleeve is locked against independent rotation, but is free to slide from a position 95 in engagement with teeth 10 to a position above cylinder 5 and out of engagement with said teeth. The lower ends of the teeth of ratchet 14 rest on portion 5' of cylinder 5 (which is also the upper end of shaft 6) 100 and the teeth are adapted to be lifted therefrom by means and for purposes herein-after mentioned.

At diametrically opposite points of sleeve 11, integral or appropriately attached arms 110 15, 15, upstand from the sleeve alongside the sides of box 13 and disposed to be guided in

the vertical guideways 16 formed in the sides of box 13. Each arm 15, near its upper end, carries a laterally extending pin 17, and on each pin 17 is eccentrically journaled a disk 18 resting edgewise upon the upper surface of frame 1. A bail-like handle 19 has its end portions fixed to disks 18, as by having each end of the bail inserted in a socket 20 on the respective disk and fastened therein by a filling of babbitt or otherwise as preferred.

The parts being in the position seen in Fig. 3, and in dotted lines in Fig. 1, the bail 19 is grasped by the operator and swung to the position seen in Figs. 2 and 5 and in full lines in Fig. 1, whereupon the sleeve 11 will have been moved, by the upward movement of pins 17 due to the eccentric mounting of disks 18, to the unlocked or disengaged position with relation to internal ratchet or locking member 10. In the course of upward movement of pins 17, the disks or eccentrics 18 shift bodily, since the pins travel in a rectilinear path, so that they move beneath lateral lugs 21, 21, outstanding from box 13. After disengagement of sleeve 11 from ratchet 10, the sleeve 11 strikes and during the final movement of bail 19 slightly lifts the box 13 and with it ratchet 14 until the weight of box 13 and the sweep carried thereby is removed from cylinder 5, the stress of such weight being delivered in operation through ratchet 14 to points 5' of cylinder 5. Shaft 6 and drum 7 are thus left entirely free to rotate substantially without frictional resistance. When the parts are to be thrown again into clutch, lever 19 is moved from the position seen in Fig. 2 to the position seen in Fig. 3, during which movement the key sleeve 11 moves downward into locking engagement with ratchets 10 and 14, the lugs 21 resting on the disks 18 and transmitting thereto the stress of the weight of box 13 and its sweep whereby any tendency of the disks to rise while pivoting on pins 17 owing to frictional resistance of the parts is entirely overcome and the disks are held down against the frame, and key sleeve 11 is forced downward until it reaches the final locked position seen in Fig. 3.

The upper flange of drum 7 is formed with a peripheral ratchet 22 engaged by a pawl 23 pivotally mounted to swing in a notch 24 formed in the upper portion of frame 1. In operation the pawl swings freely and engages the successive teeth of the ratchet 22 as the drum rotates so as to prevent back rotation of the drum in the instance of relaxation of draft pressure on box 13. When, however, it is desired that drum 7 shall be free for reverse rotation, the pawl is lifted out of the path of the ratchet, and to prevent accidental excessive elevation of the pawl, the same is provided

with a projection 25 disposed to engage the upper surface of frame 1 and prevent the pawl from moving more than an appropriate distance to clear ratchet 22, as seen in Fig. 7. To hold the pawl in this position a spring 70 pressed J-shaped bolt 26 is provided with the body of the bolt extending through the pawl and the hook or shank adapted to be swung for bringing the short end of the hook into either an aperture 27 or an aperture 28 in pawl 23. When engaging the latter, the pawl will be sustained as seen in Fig. 7, the bolt engaging the wall of frame 1, but when the bolt is disposed with its short end in aperture 27, the pawl is free to swing as seen in Fig. 6. It is quite important that projection 25 be provided, since it has frequently happened, in actual practice, that the pawl, as employed before the projection 25 was produced, would sometimes be left in a completely inverted position where it was struck by box 13 and either broke the box or some of its mechanism or cracked the frame, or at least caused the breaking of the pawl or its mounting. The possibility of all of these objectionable results is avoided by the provision of projection 25.

The lower flange 29 of spool 7 flares downwardly so as to be out of the plane of the cable engaging the drum, and also to provide a clearance space for the enlarged end of a cable engaging the eye 30, such end being beneath the flange, and yet above the horizontal plane of the outer edge of the flange so as to leave the drum free for lateral removal from frame 1 without contact of the cable end with the frame.

The operation is obvious, and consists in anchoring the frame and attaching the drum-carried cable to a stump to be pulled. 105 Sleeve 11 being in engagement with clutches 10 and 14, as seen in Fig. 3, the box 13 is revolved, as by a draft-animal operated sweep lying in box 13. Pawl 23 being in the position indicated in Fig. 6, the operation 110 continues until the stump is pulled, the pawl preventing release of the cable upon slackening of the twisting stress. When the stump has been pulled, and the cable is to be attached to another, pawl 23 is secured in the 115 released position, as seen in Fig. 7, and bail 19 is swung from the position seen in Fig. 3 to that seen in Fig. 2, whereupon the drum 7 is entirely free for paying out of the cable, and the operation is repeated.

In Fig. 11 is seen a sleeve 11^a similar in structure and function to sleeve 11, and adapted to coöperate with inner and outer clutch parts corresponding to parts 14 and 10 but differing in contour to agree with the 125 shape of sleeve 11^a. The operation is the same, and it is clear that as this sleeve is merely a locking key it may take practically any contour not perfectly circular or cylindrical so as to lock shaft 12 to shaft 6 130

when the key sleeve is interposed therebetween.

What I claim is:—

1. In a stump pulling apparatus, the combination, with a frame and a drum rotatably carried thereby and having a peripheral ratchet at its upper end, of a pawl pivoted to the upper portion of the frame and normally pendent in position for engaging the ratchet, the pawl being formed with a projection overhanging a portion of the upper surface of the frame for limiting the possible extent of upward swinging of the pawl for preventing the pawl from being moved into the path of operating means, and means above the frame for operating the drum disposed sufficiently contiguous to the frame to have its path above and at a less distance from the pivot of the pawl than the length of the pawl.
2. In a stump pulling apparatus, the combination, with a frame and a drum arranged therein, of nested shafts extending through the drum, the drum being connected to the outer shaft, means for rotating the inner shaft, a key sleeve slidably engaging the inner shaft and keyed thereto and adapted to be slid while keyed to the inner shaft to and from a position keyed to the outer shaft, an eccentrically mounted disk connected to the sleeve, and means for moving the disk about its eccentric mounting for shifting the sleeve.
3. In a stump pulling apparatus, the combination, with a frame and a drum arranged therein, of nested shafts extending through the drum, the drum being connected to the outer shaft, a sweep-receiving box connected to the inner shaft, a sleeve keyed to and slidably along the inner shaft and having an arm extending along-side one side of the box, a disk eccentrically pivoted to the arm and disposed to edgewise engage the frame, and means for oscillating the disk.
4. In a stump pulling apparatus, the combination, with a frame and a drum arranged therein, of nested shafts extending through the drum, the drum being connected to the outer shaft, a sweep-receiving box connected to the inner shaft, a sleeve keyed to and 50 slidably along the inner shaft and having an arm extending alongside one side of the box, a disk eccentrically pivoted to the arm and disposed to edgewise engage the frame, means for oscillating the disk, and means for maintaining rectilinear movement of the arm when shifted by the disk.
5. In a stump pulling apparatus, the combination, with a frame and a drum arranged therein, of nested shafts extending through the drum, the drum being connected to the outer shaft, a sweep-receiving box connected to the inner shaft, a sleeve keyed to and 55 slidably along the inner shaft and having an arm extending alongside one side of the box, a disk eccentrically pivoted to the arm and disposed to edgewise engage the frame, means for oscillating the disk, a portion of the inner shaft being disposed to rest upon a portion of the outer shaft, and means in the path of the disk for engaging the same and elevating the inner shaft toward the terminus of upward movement of the arm.
6. In stump pulling apparatus, the combination, with a frame and a drum rotatably 60 carried thereby, of a shaft extending into the drum, a key sleeve axially shiftable on the shaft and adapted to move to and from a position for locking the shaft in power transmitting relation to the drum, an eccentric 65 for actuating the sleeve, and a lug connected with the shaft and disposed to engage the eccentric for preventing movement of the eccentric in lieu of movement of the key.

In testimony whereof I affix my signature 70 in presence of two witnesses.

HENRY L. ZIMMERMAN.
